DESIGN FOR A FIRE EXTINGUISHER

Robert P. Raskob and John B. Haley, Richmond, Calif., assignors to Thermet Fire Extinguishers, Inc., Richmond, Calif., a corporation of Nevada

Application December 6, 1947, Serial No. 142,994

Term of patent 14 years

(Cl. D16—2)

To all whom it may concern:

Be it known that we, Robert P. Raskob and John B. Haley, both citizens of the United States, residing at Richmond, in the county of Contra Costa and State of California, have invented a new, original, and ornamental Design for a Fire Extinguisher, of which the following is a specification, reference being had to the accompanying drawings, forming part thereof.

The dominant features of design reside in the portion shown in full lines.

We claim:

The ornamental design for a fire extinguisher, as shown and described.

ROBERT P. RASKOB.
JOHN B. HALEY.
